UNITED STATES PATENT OFFICE.

HENRY CLAY, OF PHILADELPHIA, PENNSYLVANIA.

TELEPHONIC TRANSMITTER.

SPECIFICATION forming part of Letters Patent No. 288,017, dated November 6, 1883.

Application filed February 10, 1883. (No model.)

To all whom it may concern:

Be it known that I, HENRY CLAY, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

10 Figure 1 is an elevation, partly sectional, of my invention. Figs. 2, 3, 4, and 6 are like views of slight modifications of same. Figs. 5 and 7 are detail perspectives, and Fig. 8 is a sectional perspective, of a still further modification.

15 My invention has relation to that class of telephonic transmitters wherein the variations of pressure upon a carbon block vary the resistance therein to the passage of an electric current to vary its strength in unison with the vibrations caused by vocal utterances.

20 My invention consists of constructions and combinations, as will hereinafter be described and claimed.

25 Referring to Fig. 1 of the accompanying drawings, A represents a metallic diaphragm of a telephonic transmitter designed to be inclosed in a box or case of any desired configuration, which is not shown in the drawings, as 30 the same is well known and forms no part of my improvement.

35 B indicates a block of carbon, metal, or other suitable material, made in the shape of a ball, or is globular in outline, so that it will only present axial or diametrical points for contact with the diaphragm and its supporting-piece C. The latter is made of metal or other electrical conductor, and is provided with a socket or recess, e, for retaining the ball or block B 40 in its normal location upon the diaphragm. The latter and the supporting-piece C serve as electrodes, between which the block B is interposed.

45 The electrode C is secured to a support, E, or to the sounding-box by a strip, D, which may be flexible, springy, or rigid.

F F are the wires or conductors, designed to be arranged and connected to the diaphragm, electrode C, battery, or primary circuit of an in-

duction-coil, &c., in the usual or other desired 50 way.

The operation is obvious. As the diaphragm vibrates by speaking against it or in its neighborhood the block B is compressed thereby, and a varying contact is produced for varying 55 the strength or setting up impulses in the electric current passing therethrough, as heretofore; but as said block is round or globular in outline it presents axial points only for impingement with the electrodes. It is therefore more readily compressed, and that to a greater degree, by the varying vibrations of the diaphragm, and is more sensitively controlled thereby for the following reason: Each 60 vibration of the diaphragm produces a greater 65 compression of the block B than it would otherwise do if said block were flat or in the form of a disk or button and the electrodes impinged upon the flat surfaces thereof. Such increased compressions, therefore, correspondingly vary 70 the contact of the block B, and consequently the impulses or vibrations in the current are rendered more acute and intensified, or they 75 more nearly correspond with the amplitude of the sound-waves acting upon the diaphragm. Such intensified current variations, when they 80 operate a receiver, will therefore cause the latter to reproduce audible sounds clearer and more distinctly than has heretofore been accomplished.

A mechanical advantage is derived from the use of the ball B, which is this: As the diaphragm vibrates the ball has an oscillating or rotating motion and continually presents new or fresh poles or points for contact with the 85 electrodes. Consequently the wear of the ball is over its entire surface, and not in one spot, as is the case with flat blocks now in use.

While the above-described construction is the most simple and advantageous form of my 90 improvement, yet I do not confine myself thereto, as the electrodes may be varied in position and form and the shape of the block altered or modified in various ways to present axial or diametrical points for contact with the electrodes without departing from the spirit of my 95 invention, some of which modifications I will now proceed to describe.

In Fig. 2 a wooden diaphragm, or one of other suitable material, is substituted for the metallic diaphragm above described, in which case a metal electrode, G, is secured thereto, 5 and is in circuit with one of the wires F, as shown.

In Fig. 3 a metal diaphragm is represented, but not as forming an electrode. When so arranged, two electrodes C are employed, one 10 or both having a recess, c, but both of them having rigid spring-like or flexible supporting strips D, which are in circuit, as illustrated.

In Fig. 4 the strips D are dispensed with and two diaphragms are employed, which also serve 15 as the electrodes, one of said diaphragms being formed with a central depression or socket, c, for the ball or block B, as is more plainly illustrated in Fig. 5; or said diaphragm may have an elongated depression instead of said 20 socket, as represented in Fig. 7.

If desired, the carbon block may be formed of a disk having its edges slightly rounded, as shown in Fig. 6; or it may consist of a cylindrical block, as indicated in Fig. 8, said cylinder 25 being diametrically arranged between the electrodes, in which case one of the latter is provided with studs or projections c' c', to

keep the block in its normal position, and prevent it moving longitudinally.

It will be seen, therefore, that the block B 30 may be varied in configuration and the electrodes modified in form and position, yet in all the modifications the block is loosely held between two impinging electrodes and accomplishes the same effect as the ball. 35

What I claim is—

1. In a telephonic transmitter, the combination of a flat electrode, a recessed electrode, and an interposed ball, sphere, or cylinder presenting diametrical or polar points of contact to said electrodes, for the purpose set forth. 40

2. In a telephonic transmitter, the combination of a flat electrode, a recessed electrode having a suitable support, and a round, spherical, or cylindrical block located between said 45 electrodes and presenting diametrical contact to said electrodes.

In testimony whereof I affix my signature in presence of two witnesses.

HENRY CLAY.
